NORBERT KOCH, OF ESSEN-RELLINGHAUSEN, GERMANY, ASSIGNOR, BY MESNE ASSIGNMENTS, TO THE ALIEN PROPERTY CUSTODIAN.

AXLE SPADE FOR MOBILE ARTILLERY.

1,417,923.

Specification of Letters Patent. Patented May 30, 1922.

Application filed December 26, 1913. Serial No. 803,654.

To all whom it may concern:

Be it known that I, NORBERT KOCH, residing at Essen-Rellinghausen, Germany, a subject of the Emperor of Germany, have 5 invented a certain new and useful Improvement in Axle Spades for Mobile Artillery, of which the following is a specification.

The present invention relates to an axle spade or axle bed for mobile artillery, that 10 is anchorage organs for gun carriages, that are situated beneath or approximately beneath the wheel axles when in firing position. The object of the present invention is 15 an improvement of such spades or beds relative to their connection with the gun carriage.

In the accompanying drawing is illustrated one embodiment of the present invention, and 20 Figure 1 shows a side view of a gun carriage with an axle spade partly in section and one wheel removed, and

Fig. 2 a top plan view of a part of Fig. 1.

For anchorage of the gun carriage on 25 the ground is provided a spade having a pressure plate F and crosswise arranged ribs F¹, intended for gripping the ground. The pressure plate F carries a journal f² perpendicular to the plate, and over which 30 a sleeve g² of an upwardly extending arm G, reinforced by a flange g¹, may be pushed. At its upper end, the arm G has an abutment face g³ which may impinge against a surface h¹ of the wheel axle which is 35 cranked downwards in its middle portion, which surface h¹ runs practically parallel to the wheel axle. As connection between the arm G and the body of the carriage C serves a rigid, fork shaped bar J or other 40 similar device, which is hinged with its fork arms at c¹ to the flasks of the body C of the carriage and may be connected by means of a key bolt i¹ with the eyelets g⁴ of the arm G. Sufficient play is given the key bolt i¹ in 45 the eyelets g⁴, so that connection is possible between the arm G and the bar J even when the wheel axle does not lie perpendicularly with respect to the axis of the journal f², which might occur when the gun carriage 50 rests on uneven ground. Instead of this play the bar J may be made in two parts, which can be rotate relative to each other in the longitudinal direction. During trans- portation of the gun carriage, the bar J may

be secured by means of the key bolts i¹, to 55 the eye bolts c², Fig. 1, which are arranged on the crosspieces c³ at the under side of the carriage body.

Before firing the gun, the spade F, F¹ has 60 to be driven into the ground at the place, where the gun carriage is going to be positioned. Then the arm G with its sleeve g² is pushed over the journal f² and the gun carriage thereupon run up to the arm G until it abuts with its face h¹ against the abut- 65 ment face g³ of the arm G. Lastly, the bar J is connected with the eyelets g⁴ of the arm G by means of the key bolt i¹. The gun carriage may then be swung around the axis of the journal f², by means for instance of the 70 hand spike K. The bar J and the arm G partake in the swinging of the gun carriage.

The recoil shock caused by the firing of 75 the gun is transmitted to the spade F, F¹ through the intermediary of the bar J and the arm G. No tilting of the spade in the ground can therefore occur, as the arm G would have to partake in such a tilting 80 movement, and the arm is prevented from bending backwards with the spade through its impingement with the wheel axle H.

The now described construction possesses 85 therefore particularly this advantage over gun carriages provided with a spade for anchorage in the ground and permanently suspended between the wheels of the gun carriage, that the spade may be anchored in the ground without interference by the gun carriage. The spade may then be driven 90 directly into the ground by hammer blows, whilst with the above named older types of gun carriages a pit has first to be dug for the spade, into which the spade has to be swung. Moreover, the gun carriage wheels 95 may, with the present device, sink down into the ground independent of the spade, so that when, during firing, the carriage wheels sink into the ground at different depths, the spade is not loosened. With the described ar- 100 rangement several positions for the gun carriage may also be prepared in advance by driving spades into the ground in several places. The gun carriage will thereupon be connected, in the above described manner, 105 with one or the other of the spades. The fact that the spade and its arm may be transported separate from the gun carriage,

makes it possible to obtain a favorable distribution of load on the vehicles of the battery.

Without changing the subject matter of 5 the invention, a bed plate might for instance, be utilized instead of the spade F, F¹, which bed plate is provided with cuts for wedges or other device, that may be driven into the ground for the purpose of 10 anchoring the bed plate thereon.

I claim:

1. An anchorage device for gun carriages comprising an anchoring portion and a carriage abutting portion; a locking member 15 on the carriage detachably connected to said abutting portion, whereby said two portions will be released from the carriage upon the detachment of said locking member from said abutting portion.

20 2. An anchorage device for gun carriages comprising an anchoring portion and a carriage abutting portion; a locking member on the carriage detachably connected to said abutting portion, whereby said two portions 25 will be released from the carriage upon the detachment of said locking member from said abutting portion; said abutting portion having pivoted connection with said anchoring portion and a plain abutting surface adapted to rest against a corresponding 30 surface on the gun carriage.

3. An anchorage device for gun carriages comprising an anchoring and an abutting member; a journal on said anchoring mem-

ber, said abutting member being provided 35 with a sleeve open at both ends and adapted to be slipped over said journal; an upwardly extending arm on said sleeve and a reinforcing flange therefor, a plain surface at the free end of said arm adapted to rest against 40 a corresponding surface on the carriage; a fork with its prongs permanently hinged on the carriage, interengaging eyelets on said sleeve and on the shank of said fork, and a bolt for locking the eyelets together during 45 operation, and other eyelets on the carriage for securing the shank to the carriage by means of said bolt during travel; while said abutting member is thus detached from said fork, said anchoring member and the carriage 50 for separate transportation.

4. In a mobile mount for recoiling guns having a trail, and a pair of traction wheels; an anchorage device adapted to enter the ground between the wheels, a rigid connecting member between said anchorage device and the trail, an arm on said anchorage device constructed to abut against a surface provided on the side of the trail facing muzzlewards and running approximately parallel to the axis of said wheels.

The foregoing specification signed at Bar-
men, Germany, this 5th day of December, 1913.

NORBERT KOCH. [L. S.]

In presence of—
ALBERT NUFER,
FRANCES NUFER.
